UNITED STATES PATENT OFFICE.

WILLIAM F. BARNES, OF ROCKFORD, ILLINOIS, ASSIGNOR TO W. F. & JOHN BARNES COMPANY, OF ROCKFORD, ILLINOIS, A CORPORATION OF ILLINOIS.

DRILLING-MACHINE.

948,584.

Specification of Letters Patent.

Patented Feb. 8, 1910.

Application filed October 22, 1908. Serial No. 339,998.

To all whom it may concern:

Be it known that I, WILLIAM F. BARNES, a citizen of the United States, residing at Rockford, in the county of Winnebago and State of Illinois, have invented certain new and useful Improvements in Drilling-Machines, of which the following is a specification.

This invention relates to improvements in machines in which the tool support is capable of a lengthwise movement in order that the tool may be quickly presented to the work, a slow movement imparted to the tool while the work is being done, and a quick return of the tool to its starting position.

The object of this invention is to provide means whereby the different movements are independent of each other, that is, one must be completed before another is commenced.

In the accompanying drawings, Figure 1 is a front elevation showing the tool support in its lowest position and the parts in a position to be shifted to begin the return movement of the tool support. Fig. 2 is a partial

plan view. Fig. 3 is a vertical section on dotted line *a* Fig. 4. Fig. 4 is a vertical central section through the clutches and through the gearing on the feed shaft. Fig. 5 is an inner face representation of the inner and

upper portion of the tripping device. Fig. 6 is a section on dotted line *b* Fig. 4. Fig. 7 is an isometrical representation of the device for determining the distance of the quick advance of the tool. Fig. 8 is an

isometrical representation of the device for determining the distance the tool will continue to work. Fig. 9 is an isometrical representation of the device for stopping the return of the tool support. Figs. 10, 11, 12

and 18 are representations of the tripping devices in their various positions. Fig. 14 is a vertical section of the tool support and its driving pinion. Fig. 15 is an inner face

representation with the parts in their normal positions. Figs. 16, 17 and 18 are representations of the starting lever and the parts operated by it. Fig. 19 is a partial section of the mechanism for giving different speeds to the quick advance and return movements.

Fig. 20 is an isometrical representation of the arm 28, lower portion 31 of the latch and rod 96. Fig. 21 is an isometrical representation of the latch 107. Fig. 22 is an isometrical representation of the latch 105. Fig. 23 is an isometrical representation of the starting lever.

My improvements are shown applied to what is known as a drill press, said drill press comprising the main frame 1 supporting the main driving shaft 2, and the reciprocating sleeve 3.

The bevel gears 4 and 5 form a connection between the main driving shaft and drill spindle 5½ carried by the sleeve, and as the driving shaft is constantly rotated, the drill spindle will also be rotated. A belt connection with the cone pulley 6 mounted on the main driving shaft will impart a rotary movement to the shaft. The sleeve has a toothed rack 7 movable with it. A feed shaft 8 is supported by the main frame and supports a pinion 9 which meshes with the toothed rack. A hand wheel 10 has a connection with one end of the feed shaft. A bracket is supported by the main frame and comprises the two vertical bars 11 and 12, lower bar 13 and top bar 14. The vertical bar 12 is supported by a hub 15 extending from the main frame. An arm 16 extends from the upper bar 14, and has a connection 80 with the rod 17 extending from the main frame.

The feed shaft 8 has a bearing in the vertical bar 11 of the bracket. A shaft 18 is supported by the two vertical bars 11 and 12, and is located some distance above the feed shaft 8 and parallel therewith. To the feed shaft 8 is pinned a spur-toothed pinion 19, also a worm wheel 20.

The lower bar 13 of the bracket is formed 90 with a horizontal rectangular groove-way 21 within which is located a support 22 pivoted at the point 23 between the ears 24 extending rearward from the lower bar 13. This support has a lengthwise central opening within 95 which is located a shaft 25. To the center portion of this shaft 25 is secured a worm 26, and to one end of this shaft is secured a beveled toothed-wheel 27. As the worm 26 is supported in a pivotal manner, it can be 100 moved into engagement with the worm-wheel 20 by means now to be described and can be held in such engagement. From one end of the support 22 extends an arm 28 and is located at right angles thereto. From 105 the vertical bar 12 of the bracket extends a

lug 29 to which is pivoted a latch comprising an upper end 30, a lower hooked end 31 and a handle 32. A spring 33 is located between the lower bar 13 of the bracket, and the lower hooked end of the latch.

When the worm 26 is moved into engagement with the worm-wheel 20, the arm 28 will be raised until the hooked lower end 31 of the latch receives the lower edge of the arm 28, as shown in Fig. 6, thereby holding the worm in engagement with the worm-wheel.

The arm 16 supports a tubular bearing 34 within which is located a shaft 35. To the lower end of this shaft is secured a beveled-toothed pinion 36 held in mesh with the beveled-toothed wheel 27. To the upper end of the shaft 35 is secured a miter toothed-wheel 37. A shaft 38 is secured in suitable bearings; to one end of which is secured a miter toothed-wheel 39 meshing with the miter toothed-wheel 37. To the other end of this shaft 38 is secured a plate 40 having a series of concentric rings of teeth 41.

To the main driving shaft 2 is secured a toothed pinion 42. A frame 43 is loosely mounted on the driving-shaft 2, and is intended to be supported by the main-frame, the connection being omitted in order to more clearly show other parts, and supports a toothed pinion 44, and a shaft 45. This shaft 45 has a toothed pinion 46 secured to it which meshes with the toothed pinion 44, and it in turn meshes with the toothed pinion 42, thereby forming a driving connection between the main driving shaft 2 and the shaft 45. The shaft 45 is provided with a lengthwise groove 47, a toothed pinion 48 has a feather connection with the groove in order that it may be moved bodily in the lengthwise direction of the shaft so that it may be placed in engagement with the various concentric rings of teeth 41.

Thus far described, a rotary movement is imparted to the drill spindle by the gear connection with the main driving shaft 2.

By reason of the gear connection between the main driving shaft and worm-wheel 20, when the worm 26 is in engagement with the worm-wheel, a connection will be formed between the main driving shaft and feed shaft which will rotate it, and the toothed pinion 9 connected therewith being in engagement with the toothed rack 7, the toothed rack 55 will be moved downward toward the work, and as the toothed rack is a part of the sleeve supporting the tool, the tool will engage the work.

In some of the figures of the drawings, the gearing is covered; but in other figures the gearing is shown.

To the shaft 18 is pinned a spur-toothed-wheel 49 which meshes with the toothed pinion 19 pinned to the feed shaft 8. This spur-toothed-wheel 49 has a flange 50 ex-

tending from it. Upon the shaft 18 are loosely mounted two beveled-toothed wheels 51 and 52 facing each other.

A shaft 53 is supported in bearings 54 and 55 and is rotated by a gear connection 70 with the shaft 35, said gear connection comprising two spur-toothed-wheels 56 and 57 fixedly connected to the shaft 53. A shaft 58 is supported in bearings 59 and to one end of this shaft is fixedly connected a beveled-toothed-wheel 60 which meshes with a beveled-toothed-wheel 61 secured to the shaft 35. Two spur-toothed-wheels 62 and 63 are loosely mounted on the shaft 58 and mesh with the spur-toothed-wheels 56 and 57. A sliding clutch member 64 has a connection with the shaft 58 and rotates therewith. The sliding clutch member can be placed in engagement with either of the spur-toothed-wheels 62 and 63, and as the wheels are of different diameters, different speeds will be transmitted to the shaft 53. This shaft 53 has a beveled toothed-pinion 64 secured to it which meshes with the beveled toothed-wheels 51 and 52 and which is constantly rotated, thereby imparting a rotary movement to one of the beveled toothed-wheels in one direction and a rotary movement to the other beveled toothed-wheel in the opposite direction.

On the shaft 18 between the beveled toothed-wheels 51 and 52 is located a clutch having the saw-toothed faces 65 and 66 and circumferential groove 67. This clutch has a sliding connection with the shaft 18 by the feather 68 engaging a groove in the clutch.

From the upper bar 14 of the bracket depends an arm 69 having a transverse opening within which is located a short shaft 70. To one end of this shaft is pinned an arm having a depending end 71 provided with a stud 72 entering the facial groove 67 of the clutch, and an uprising section 73 having a stud 74 extending from its upper end. To the other end of this short shaft 70 is pinned a bell-crank lever having one branch 75 depending from the shaft, and provided with a stud 76 entering the facial groove 67 of the clutch, and the other branch 77 extending at substantially right angles to the branch 75. This branch 77 supports three studs 78, 79 and 80, made adjustable in the direction of their length, and held when adjusted by a set screw for each stud.

From the free end of the branch 77 depends an arm 81 to the lower end of which is connected a spiral spring 82, the lower end of the spring being connected to a stationary part of the machine. From the lower end of the arm 81 extends a wing 83, which supports a screw 84.

The flange 50 of the spur-toothed-wheel 49 supports three rings 85, 86 and 87 shown

at Figs. 7, 8 and 9. The ring shown at Fig. 7 is split, and its ends are connected by the screw 88, and by means of this screw the ring is clamped in engagement with the flange in a manner to permit its adjustments circumferentially around the flange. This ring has a cam-surface 89 projecting beyond one of its edges, and the cam surface has a portion 90 extending toward the center of the ring. The ring 86 is clamped in connection with the flange 50 by the screw 91 and has a cam surface 92 extending from its face. The ring 87 is clamped in connection with the flange 50 by the screw 93 and has a projection 94 extending from its face. The ring 87 is clamped in connection with the flange so that its projection 94 will engage the upper end 30 of the latch. The ring 86 is so located in connection with the flange 50 that the cam-surface 92 will engage the stud 78, and the ring 85 is located in connection with the flange 50 at its outer edge. The bar 12 of the bracket has its upper portion provided with a rectangular opening 95.

25 To the free end of the arm 28 is connected a rod 96 by a screw 97 located in the elongated slot 98 of the rod. A spring 99 has one end connected to the rod 96, and its other end to the arm 28. To the upper end 30 of the rod 96 is secured a floating dog comprising the front plate 100, a rear plate 101, and a stem 102 connecting the plates. The stem is located in the rectangular opening 95 in the upper portion of the bar 12. The rear plate 101 is located beneath the studs 79 and 80 depending from the branch 77 of the bell crank lever.

To the bar 13 of the bracket is connected a stud 108 upon which is pivotally mounted a bar 104, a catch 105, and a starting lever 106. The bar 104 supports a latch 107 in a pivotal manner. The catch 105 has a stud 108 extending from its side facing the starting lever. A coiled spring 109 has one end connected to a projection 110 extending from the latch 107 and its other end is connected to a projection 111 extending from the catch 105. The starting lever 106 has two cam-surfaces 112 and 113. An arm 114 extends from the rear of the arm 81 and its free end is provided with a vertically arranged opening. A rod 115 has its lower end pivotally connected with the free end of the bar 104, and its upper end passes through the opening in the arm 114. The upper portion of the rod 115 is screw-threaded and a nut 116 is placed beneath the arm 114. A spring 117 is placed around the rod above the arm 114 and a nut 118 is placed above the spring.

In Figs. 2, 3, 4, 5 and 6 the parts are in the positions they occupy when the sleeve and drill-spindle are elevated. The tool and the beveled-toothed gears 51 and 52 are rotating idly and the clutch between the bevel

toothed-wheels 51 and 52 stand free of both wheels.

The operation is as follows: The starting lever 106 is raised from the position shown in Fig. 15 to that shown in Fig. 16 which will cause the cam-surface 112 to engage the lower end of the rod 96 and raise it into the position shown at Fig. 16. Before the starting lever is moved, the catch 105 will engage a projection 119 extending from the arm 28 thereby preventing the upward movement of the arm which will hold the worm 26 out of engagement with the worm-wheel 20 thereby holding the work-feed out of action. As the rod 96 moves upward, the spiral spring 99 will be extended sufficiently to raise the arm 28 after it is released, thereby throwing the work-feed into action. The upward movement of the rod 96 will elevate the floating dog. The stud 79 of the bell-crank resting on the upper edge of the rear plate 101 of the floating dog forms a connection between the floating dog and bell-crank lever, and when the floating dog is elevated, the bell-crank lever will be rocked which will move the clutch located between the beveled-toothed-wheels 51 and 52 so that its toothed face 65 will interlock with the teeth 120 of the bevel-toothed-wheel 51 as shown at Fig. 11. This connection will impart a rotary movement to the spur-toothed-wheel 49 through the pinion 19 to the feed-shaft 8, and through the pinion 9 to the toothed-rack 7 of the sleeve in a downward direction. The gear connection with the sleeve is such that the sleeve will have a quick downward movement. The raising movement of the arm 77 of the bell-crank will pull up on the rod 115 and move the bar 104 sufficiently to permit the latch 107 to engage the stud 108 extending from the catch 105 as shown at Fig. 16. As the toothed-wheel 49 is given a partial rotation during the quick downward movement of the tool support, the rings 85, 86 and 87 will be carried with it. The ring 85 is adjusted in connection with the flange 50 of the toothed-wheel so that when the tool holder has descended the proper distance, the cam surface 89 of the ring will engage the rear plate 101 of the floating dog and move the upper end of the floating dog so that the rear plate of the floating dog will move free of the stud 79 thereby allowing the arm 77 of the bell-crank to descend until the stud 80 rests in contact with the upper edge of the rear plate 101 of the floating dog as shown at Fig. 12. This movement of the bell-crank will move the clutch located between the beveled-toothed-wheels 51 and 52 free of the beveled-toothed-wheel 51 which will break the driving connection with the toothed-wheel 51 and stop the quick descending movement of the sleeve. The dropping of the arm 77 of the bell-crank

will force the bar 104 down, carrying the latch 107 with it. As the latch 107 is in engagement with the stud 108 of the catch 105, the downward movement of the latch 107 will force the catch from its engagement with the projection 119 extending from the arm 28, thereby permitting the spring 99 to exert its force on the arm 28, and raise it which will throw the worm 26 into engagement with the worm-wheel 20 and will be held elevated by the lower hooked end 31 of the latch passing under the bar. The finger 121 extending from the latch 107 will come in contact with the screw 122 supported on a fixed part of the frame and the further downward movement of the bar 104 will free the latch of its engagement with the stud 108 of the catch. It will thus be obvious that the quick advancing mechanism will be thrown out of operation prior to the time the working feed means is thrown into operation. The sleeve will carry the tool downward slowly, and through its connection with the worm-wheel 20, will move the toothed-wheel 49 slowly in the same direction it was moving while a quick movement was being imparted to the tool support.

When the tool has finished its work, the projection 94 carried by the ring 87 will engage the upper end 30 of the latch and move the latch sufficiently to release its lower hooked end 31 from engagement with the arm 28, thereby permitting the arm 28 to drop, carrying the worm 30 with it, which will disengage the worm from the worm-wheel 20 and stop the slow downward movement of the tool. This dropping movement of the arm 28 will carry the floating dog with it, thereby permitting the bell-crank to move, which will move the clutch located between the bevel-toothed-wheels 51 and 52 into engagement with the teeth 123 of the bevel-toothed-wheel 52, thereby forming a connection between the toothed-wheel 64 and the sleeve, which will move the toothed-wheel 51 in a direction opposite to that at which it was previously moving as shown at Fig. 18. This movement of the toothed-wheel 51 will, through the gear connection with the sleeve impart a quick return movement to the sleeve and drill-spindle until the cam surface 92 of the ring 86 comes in contact with the stud 78, which will move the bell-crank, and through it move the clutch from engagement with the bevel-toothed-wheel 52 into a position where it will be free of both bevel-toothed-wheels 51 and 52 and will remain at rest. Upon the last movement being imparted to the bell-crank the stud 78 will be elevated sufficiently to permit the spring 127 shown in Fig. 1 to move the floating dog laterally so that the rear plate 101 thereof will remain at rest beneath the stud 79, when all parts will assume their normal positions. The spring 82 is employed to move the clutch

from its engagement with the bevel-toothed-wheel 51 into engagement with the bevel-toothed-wheel 52. The cam surface 90 on the ring 86 will engage the screw 84 and move the bell-crank, should the spring 82 fail to move it. By this arrangement the tool is given a quick advance to the work, a slow movement while doing its work, and a quick return after the work has been completed. It is only necessary to raise up on the starting lever 106 to start the mechanism in operation, when the various movements are automatically accomplished. By pressing down on the handle 82 extending from the latch, the sleeve can be instantly returned to its normal or starting position.

To the top bar 14 of the bracket is pivoted a lever 124 having a cam-notch 125 in its front edge. By means of this lever the projection 74 extending from the arm 73 will be received in the cam-notch which will hold the sliding clutch free of both wheels, 51 and 52 when the sleeve and drill-spindle can be reciprocated by means of the hand wheel 10.

The set-screw 126 limits the downward movement of the worm support.

Should the spring 99 become broken or lose its elasticity so that it would not move the worm 26 into engagement with the worm-wheel 20 to start the work-feed, the operator can move the starting lever so that the cam surface 113 will be brought against the under face of the bar 28 and raise it after the catch has released it, until the lower hooked end 31 of the latch passes under the bar, which will hold the bar and worm elevated during the time the work-feed is in operation.

It will be noticed that the quick-advancing mechanism does not throw into action the work-feed, but simply removes a catch which holds the work-feed out of action, and after the latch has become disengaged, a spring throws the work-feed into action.

If the spring fails to work, the work-feed would not become active unless the operator raised the starting lever sufficiently to throw the worm into engagement with the worm-wheel. It will further be noticed that the quick advancing mechanism ceases before the work-feed begins, which must be the case because both of such feeds operate on the feed shaft positively through different means.

It will further be noticed that the quick advancing mechanism, work-feed mechanism, and quick return mechanism are driven from the same shaft that rotates the drill-spindle. It will further be noticed that the quick advancing mechanism, work-feed mechanism and quick return mechanism are positively driven so that no opportunity is offered for slippage, and when the quick-advancing mechanism, work feed mechanism and quick return mechanism are inactive no waste of power is taking place.

105

with the exception of idly turning the gearing. As the quick advancing mechanism ceases before the work-feed mechanism begins they act successively which would not be the case if both were in operation at the same time, in that instance they would act conjointly.

The expressions "quick-feed": "work-feed" and "quick return" used throughout the specification and claims denote the advance downward movement of the drill-spindle to the work, the further downward movement of the drill-spindle while the tool is doing its work, and the return movement of the drill-spindle to its starting position. The work feed runs at considerable less speed than the quick-feed and the quick return, and the word "quick" is used with this understanding.

While in the drawings I have shown my improvements in a drilling machine in which a quick return movement is imparted to the drill spindle I have not deemed it necessary to embody such element in most of the claims as my improvements are complete without such movement and it would only be adding an old movement to my improvement without in any manner changing the nature of my improvements.

I claim as my invention.

1. In a drilling machine, in combination, a rotatable and longitudinally movable drill spindle, a quick advancing mechanism and work feed mechanism for successively advancing the spindle in the same direction, means for starting the quick advancing mechanism, means for holding the work feed mechanism out of action during the quick advancing movement of the spindle, automatic means for first stopping the quick advancing mechanism and afterward releasing said holding means to permit the work feed mechanism to be placed into action.

2. In a drilling machine, in combination, a rotatable and longitudinally movable drill spindle, a quick advancing mechanism and work feed mechanism for successively advancing the spindle, means for starting the quick advancing mechanism, means for holding the work feed mechanism out of action during the quick advancing movement of the spindle, means for stopping the quick advancing mechanism, means controlled by said stopping means for throwing the work feed mechanism into action after the stopping of the quick advancing mechanism, and means for stopping the work feed mechanism.

3. In a drilling machine, in combination, a rotatable and longitudinally movable drill spindle, a quick advancing mechanism and work feed mechanism for successively advancing the spindle, means for starting the quick advancing mechanism, means for holding the work feed mechanism out of action

during the quick advancing movement of the spindle, means adapted to be operated by the quick advancing mechanism for releasing said holding means, means for stopping the quick advancing mechanism, and means independent of the quick advancing mechanism for throwing the work feed mechanism into action after the stopping of the quick advancing mechanism.

4. In a drilling machine, in combination, a rotatable and longitudinally movable drill spindle, a quick advancing mechanism and work feed mechanism for successively advancing the spindle, means for starting the quick advancing mechanism, means for stopping the quick advancing mechanism, means controlled by the stopping mechanism for automatically throwing the work feed mechanism into action after the stopping of the quick advancing mechanism, and means for stopping the work feed mechanism.

5. In a drilling machine, in combination, a rotatable and longitudinally movable drill spindle, a quick advancing mechanism and work feed mechanism for successively advancing the spindle, means for starting the quick advancing mechanism, means for stopping the quick advancing mechanism, and automatically operated means for starting the work feed mechanism upon cessation of movement of the quick advancing mechanism.

6. In a drilling machine, in combination, a rotatable and longitudinally movable drill spindle, a quick advancing mechanism and work feed mechanism for successively advancing the spindle, means for starting the quick advancing mechanism, a latch for holding the work feed mechanism out of action during the quick advancing movement of the spindle, means controlled by the quick advancing mechanism for automatically operating the latch to release and permit the work feed mechanism to be placed into action, and means for stopping the quick advancing mechanism.

7. In a drilling machine, in combination, a rotatable and longitudinally movable drill spindle, a quick advancing mechanism and work feed mechanism for successively advancing the spindle, means for starting the quick advancing mechanism, a latch for holding the work feed mechanism out of action during the quick advancing movement of the spindle, automatic means for operating the latch, to release the work feed mechanism, means for stopping the quick advancing mechanism, automatic means for throwing the work feed mechanism into action when released by the latch, and means for stopping the work feed mechanism.

8. In a drilling machine, in combination, a rotatable and longitudinally movable drill spindle, a feed shaft for the spindle, a worm wheel fixedly connected with the feed shaft,

- 1 a work feed mechanism for the spindle, including a worm that meshes with the worm wheel, a quick advancing mechanism for the spindle operating through the feed shaft, 5 means for starting the quick advancing mechanism, and means for automatically stopping the quick advancing mechanism and afterward starting the work feed mechanism.
- 10 9. In a drilling machine, in combination, a rotatable and longitudinally movable drill spindle, a feed shaft for the spindle, two gears fixedly connected to the feed shaft, a quick advancing mechanism for the spindle 15 operating through one of said gears, a work feed mechanism for the spindle operating through the other of said gears, means for starting the quick advancing mechanism, and means for automatically stopping the 20 quick advancing mechanism and afterward starting the work feed mechanism.
- 10 10. In a drilling machine, in combination, a rotatable and longitudinally movable drill spindle, a feed shaft for the spindle, two 25 gears fixedly connected to the feed shaft, a quick advancing mechanism, and a quick return mechanism for the spindle, operating through one of said gears, a work feed mechanism for the spindle operating through 30 the other of said gears, means for starting the quick advancing mechanism, means for automatically stopping the quick advancing mechanism and after such stoppage starting the work feed mechanism, means for automatically stopping the work feed mechanism, and means for automatically starting the quick return mechanism after the stoppage of the work feed mechanism.
- 11 11. In a drilling machine, in combination, 40 a rotatable and longitudinally movable drill spindle, a quick advancing mechanism, a work feed mechanism and a quick return mechanism for successively moving the spindle, means for starting the quick advancing mechanism, means for automatically stopping the quick advancing mechanism and starting the work feed mechanism, means for automatically stopping the work feed mechanism and starting the quick return mechanism, and automatically operated 50 means for preventing the operation of the work feed mechanism before the completion of the quick advancing mechanism.
- 12 12. In a drilling machine, in combination, 55 a rotatable and longitudinally movable drill spindle, a feed shaft, for the spindle, two gears fixedly connected with the feed shaft, a quick advancing mechanism for the spindle operating through one of said gears, a work feed mechanism for the spindle operating through the other of said gears, means for starting the quick advancing mechanism, means for automatically stopping the quick advancing mechanism and after such stoppage, starting the work feed mechanism, and
- 13 automatically operated means for positively preventing the operation of the work feed mechanism before the completion of the quick advancing mechanism.
- 13 13. In a drilling machine, in combination, 70 a rotatable and longitudinally movable drill spindle, a feed shaft for the spindle, two gears fixedly connected with the feed shaft, a quick advancing mechanism and a quick return mechanism for the spindle operating 75 through one of said gears, a work feed mechanism for the spindle operating through the other of said gears, means for starting the quick advancing mechanism, means for automatically stopping the quick advancing mechanism and starting the work feed mechanism after such stoppage, means for automatically stopping the work feed mechanism, means for starting the quick return mechanism, and automatically operated 80 means for positively preventing the operation of the work feed mechanism during the operation of the quick advancing mechanism.
- 14 14. In a drilling machine, in combination, 85 a rotatable and longitudinally movable drill spindle, a feed shaft for the spindle, two gears fixedly connected with the feed shaft, a quick advancing mechanism for the spindle operating through one of said gears, a work feed mechanism for the spindle operating 90 through the other of said gears, and means automatically controlled by the quick advancing mechanism for rendering the work feed mechanism active only after the quick advancing mechanism has ceased to operate.
- 15 15. In a drilling machine, in combination, 95 a rotatable and longitudinally movable drill spindle, a feed shaft for the drill spindle, two gears fixedly connected with the feed shaft, a quick advancing mechanism and a quick return mechanism for the spindle operating through one of said gears, a work feed mechanism for the spindle operating 100 through the other of said gears, means automatically operated by the quick feed mechanism for rendering the work feed mechanism active only after the quick advancing mechanism has ceased to operate, and means automatically operated by the work feed mechanism for rendering the quick return 105 mechanism active only after the work feed mechanism has ceased to operate.
- 16 16. In a drilling machine, in combination, 110 a rotatable and longitudinally movable drill spindle, a feed shaft for the spindle, two gears adapted to rotate the shaft, a quick advancing mechanism for the spindle operating through one of said gears, a work feed mechanism for the spindle operating 115 through the other of said gears, and automatically operated means for preventing the operation of the work feed mechanism before the completion of the quick advancing mechanism.
- 17 17. In a drilling machine, in combination, 120

5 a rotatable and longitudinally movable drill spindle, a shaft for rotating said spindle, a quick advancing mechanism, a work feed mechanism and a quick return mechanism for the spindle all driven from the same shaft, and means for changing the speed of the quick feed mechanism and quick return mechanism independently of the work feed mechanism.

10 18. In a drilling machine, in combination, a rotatable and longitudinally movable drill spindle, a quick advancing mechanism and work feed mechanism for successively advancing the spindle, a latch for holding the 15 work feed mechanism out of action during the quick advancing movement of the spindle, means for releasing the latch, means for stopping the quick advancing mechanism, means adapted to be moved by the operator 20 for starting the quick advancing mechanism, and automatic means separate from the latch for effecting a further movement of said last-mentioned means to throw in the work feed mechanism after the quick advancing mechanism has ceased to operate.

19. In a drilling machine, in combination, a rotatable and longitudinally movable drill spindle, a quick advancing mechanism and work feed mechanism for successively advancing the spindle, means for holding the work feed mechanism out of action during the quick advancing movement of the spindle, automatic means for operating the holding means to release the work feed mechanism, means for stopping the quick advancing mechanism, and means adapted to be moved by the operator for starting the quick advancing mechanism and capable of further movement to throw in the work feed mechanism after the quick feed mechanism has ceased to operate.

20. In a drilling machine, in combination, a rotatable and longitudinally movable drill spindle, a quick advancing mechanism and work feed mechanism for successively advancing the spindle, means for holding the work feed mechanism out of action during the quick advancing movement of the spindle, means for automatically moving the 50 holding means to release the work feed mechanism, means for stopping the quick advancing mechanism, and a lever adapted to be moved by the operator, said lever having two cam surfaces, one cam surface adapted to move the quick advancing mechanism into action and the other cam surface adapted to move the work feed mechanism into action.

21. In a drilling machine, in combination, a rotatable and longitudinally movable drill spindle, a quick advancing mechanism and work feed mechanism for successively advancing the spindle, means for starting the quick advancing mechanism, means for stopping the quick advancing mechanism, and

automatically operated means for starting the work feed mechanism after the quick advancing mechanism has ceased to operate.

22. In a drilling machine, the combination with a rotatable and longitudinally movable drill spindle, of a quick advancing mechanism and a work feed mechanism therefor, a driving device for the quick advancing mechanism, means for clutching said mechanism to and unclutching it from the driving device, means for maintaining the work feed mechanism inactive while the quick advancing mechanism is in operation, and mechanism controlled by the clutching and unclutching mechanism for throwing the work feed mechanism into action when the quick advancing mechanism is unclutched from the driving device.

23. In a drilling machine, the combination with a rotatable and longitudinally movable drill spindle, of quick advancing mechanism and a work feed mechanism therefor, a driving device for the quick advancing mechanism, means for connecting said mechanism to and disconnecting it from the driving device, a latch for maintaining the work feed mechanism inactive while the quick advancing mechanism is in operation, and mechanism controlled by the connecting and disconnecting means for operating the latch to release the work feed mechanism.

24. In a drilling machine, the combination with a rotatable and longitudinally movable drill spindle, of quick advancing mechanism and a work feed mechanism therefor, a driving device for the quick advancing mechanism, means for connecting said mechanism to and disconnecting it from the driving device, a motor device for moving the work feed mechanism into operation, a latch for holding the work feed mechanism out of operation, and mechanism controlled by the connecting and disconnecting means for operating the latch to release the work feed mechanism.

25. In a drilling machine, the combination with a rotatable and longitudinally movable drill spindle, of a quick advancing mechanism and a working feed mechanism therefor, a driving device for the quick advancing mechanism, a clutch element for connecting the driving device to and disconnecting it from the quick advancing mechanism, means for moving the clutch element, means for holding the work feed mechanism inactive while the driving device is clutched to the quick advancing mechanism, and mechanism operated by the clutch moving means to release the work feed mechanism.

26. In a drilling machine, the combination with a rotatable and longitudinally movable drill spindle, of a quick advancing mechanism and a work feed mechanism therefor, a driving device for the quick ad-

vancing mechanism, a clutch element for connecting the driving device to and disconnecting it from the quick advancing mechanism, means for moving the clutch element, 5 a latch for holding the work feed mechanism inoperative while the driving device is clutched to the quick advancing mechanism, and operating means for the latch automatically controlled by the clutch moving 10 means.

27. In a drilling machine, the combination with a rotatable and longitudinally movable tool spindle, of a work feed mechanism and a quick advancing mechanism therefor, means for moving the work feed mechanism into coöperative relation with so as to drive the spindle, a latch for holding the work feed means against movement by said means, and means for disengaging 20 the latch from the work feed mechanism to permit the moving means to move the same into said coöperative relation.

28. In a drilling machine, the combination with a rotatable and longitudinally movable tool spindle, of a work feed mechanism and a quick advancing mechanism therefor, means for moving the work feed mechanism into coöperative relation with so as to drive the spindle, a latch for holding the work feed against movement by said means, and means for operating the latch, 30 said means including a catch that detachably engages the latch to disengage said latch from the work feed mechanism and permit it to be moved into said coöperative relation, and means for disengaging the latch and catch.

29. In a drilling machine, the combination with a rotatable and longitudinally movable tool spindle, of a work feed mechanism, a quick advancing mechanism therefor, means for moving the work feed mechanism into coöperative relation with so as to drive the spindle, and means for holding 40 said work feed mechanism inactive and releasing it to permit it to operate, said means including two latches, one of which detachably engages the work feeding mechanism, the other engaging the first-mentioned latch, 50 to disengage it from the work feed mechanism, and means for operating the second latch and disengaging it from the first latch.

30. In a drilling machine, the combination with a rotatable and longitudinally movable tool spindle, of a work feed mechanism, a quick advancing mechanism therefor, means for moving the work feed mechanism into coöperative relation with so as to drive the spindle, and means for holding 55 said work feed mechanism inactive and releasing it to permit it to operate, said means including a latch that detachably engages the work feed mechanism, a swinging arm, another latch on the swinging arm that engages the first-mentioned latch, means for

swinging the arm, and a device for operating the latch on the arm to disengage it from the first latch.

31. In a drilling machine, the combination with a rotatable and longitudinally movable tool spindle, of work feed mechanism, a quick advancing mechanism therefor, said work feed mechanism including a worm wheel, and a worm movable into and out of coaction with the wheel, a support for the worm including an arm, a spring for moving the support in one direction, a latch that engages the arm to hold it against movement by the spring, a swinging arm, a latch pivoted on the swinging arm and detachably engaging the first-mentioned latch, means controlled by the quick advancing mechanism for effecting the swinging movement of the arm, and a stop located in the path of movement of the latch on the swinging arm to operate the same. 85

32. In a drilling machine, the combination with a rotatable and longitudinally movable tool spindle, of mechanism for effecting a working feed thereof, mechanism for effecting a quick advance of the tool spindle, means for throwing the quick advancing mechanism into operation including a pivoted lever, and a latch for holding the work feed mechanism inactive while the quick 90 advancing mechanism is in operation, said latch being pivoted on an axis that is substantially coincident with the axis of the lever.

33. In a drilling machine, the combination with a rotatable and longitudinally movable tool spindle, of mechanism for effecting a working feed thereof, mechanism for effecting a quick advance of the spindle, a pivot, means for throwing the quick advance mechanism into operation, including a lever journaled on the pivot, and a latch for holding the work feed mechanism inactive while the quick advance mechanism is in operation, said latch being also journaled on 100 said pivot.

34. In a drilling machine, the combination with a rotatable and longitudinally movable tool spindle, of mechanism for effecting a working feed thereof, mechanism for effecting a quick advance of the tool spindle, including a clutch, manually operated means for shifting the clutch to throw the quick advancing mechanism into operation, means for locking the work feed 115 mechanism out of operation, automatic means for moving the clutch to throw the quick advance mechanism out of operation, and means operated by said automatic means to release the work feed mechanism. 120

35. In a drilling machine, the combination with a rotatable and longitudinally movable tool spindle, of mechanism for effecting a working feed thereof, mechanism for effecting a quick advance of the spindle, 125

including a clutch, a clutch shifting device, manually operated means for operating the shifting device to throw the quick advancing mechanism into operation, automatic means 5 operating on the clutch shifting device to make the quick advancing mechanism inactive, means for holding the work feed mechanism inactive, and means operated by the clutch shifting device for releasing the 10 work feed mechanism.

36. In a drilling machine, the combination with a rotatable and longitudinally movable tool spindle, of mechanism for effecting a working feed thereof, mechanism 15 for effecting a quick advance of the spindle including a clutch, a clutch shifting device, manually operated means for operating the shifting device to throw the quick advance mechanism into operation, automatic means 20 for operating the clutch shifting device to make the quick advance mechanism inactive, a latch detachably engaging the work feed mechanism to hold it inactive, and means operated by the clutch shifting device for 25 operating the latch to release the work feed mechanism.

37. In a drilling machine, the combination with a rotatable and longitudinally movable tool spindle, of mechanism for effecting a working feed thereof, mechanism 30 for effecting a quick advance of the spindle, an actuating device for the latter mechanism, a clutch element for connecting the actuating device to the quick advancing 35 mechanism, a swinging arm for operating the clutch element, manually operated means for moving the arm in one direction, automatic mechanism for effecting the movement of the arm in the other direction, a 40 latch for holding the work feed mechanism inactive, and operating means for said latch actuated by the arm.

38. In a drilling machine, the combination with a rotatable and longitudinally 45 movable tool spindle, of working feed mechanism therefor including a shiftable worm, a device for automatically moving the worm in one direction, a latch for holding the worm against movement by the device, quick 50 advance mechanism for the tool spindle, an actuating device therefor, a shiftable clutch for connecting the actuating device to the quick advancing mechanism, a swinging arm for shifting the clutch, manually operated 55 means engaging the arm to move the same in one direction, a swinging arm having a latch that detachably engages the first mentioned latch, a connection between said arm and the clutch shifting arm, and a stop disposed in 60 the path of movement of the latch on the arm for operating the same.

39. In a drilling machine, the combination with a rotatable and longitudinally movable 65 drill spindle, of a quick advancing mechanism and a work feed mechanism for success-

sively advancing the spindle, means for starting the quick advancing mechanism, means for holding the work feed mechanism out of coaction during the quick advancing movement of the spindle, means controlled 70 by the quick advancing mechanism for releasing said holding means, means for stopping the quick advancing mechanism, and a spring separate from the holding means for moving the work feed mechanism into action when released from the holding means. 75

40. In a drilling machine, the combination with a rotary and reciprocatory drill spindle, of means for effecting a working feed thereof, said means being movable into and 80 out of driving coaction with the spindle, a quick return mechanism, a clutch member for connecting and disconnecting the quick return mechanism and the spindle, and means automatically operating with the 85 working feed means on its movement out of coaction with the spindle for moving the clutch member to a position to connect the quick return mechanism and the spindle.

41. In a drilling machine, the combination 90 with a rotary and reciprocatory drill spindle, of means for effecting a working feed thereof, a movable support for the working feed means that carries the same into and out of driving coaction with the spindle, a 95 quick return mechanism, a clutch member for connecting the quick return mechanism and the spindle, and means connected to and movable with the support for moving the clutch member to a position to connect the 100 quick return mechanism and the spindle when the working feed means moves out of coaction with the spindle.

42. In a drilling machine, the combination 105 with a rotary and reciprocatory drill spindle, of means for effecting a working feed thereof, a movable support for the working feed means that carries the same into and out of driving coaction with the spindle, a quick return mechanism, a clutch member 110 for connecting and disconnecting the quick return mechanism and the spindle, means connected to and movable with the support for moving the clutch member to a position to connect the quick return mechanism and the spindle when the working feed means moves out of coaction with the spindle, a latch for holding the support with the working feed means in driving coaction with the spindle, and means for automatically operating the latch to release the support and permit it to carry the working feed means out of coaction with the spindle. 115

43. In a drilling machine, the combination 120 with a rotary and reciprocatory drill spindle, of a feed shaft therefor, a swinging support, working feed means including a gear mounted on the support and movable into and out of coacting driving relation with the feed shaft, a latch for holding the sup- 125 port, and a clutch member for connecting the 130

port with the gear in such driving coaction, quick return mechanism including a device geared to the feed shaft, a driving member, a clutch for connecting and disconnecting the driving member and the device, and actuating means for the clutch connected to the swinging support and operated thereby on its movement to carry the gear out of driving coaction with the feed shaft.

10 44. In a drilling machine, the combination of a rotatable and longitudinally movable drill spindle, a feed shaft for reciprocating the spindle, a quick advancing mechanism, a

work feed mechanism, a quick return mechanism, automatic means for separately and successively connecting said quick advancing work feed and quick return mechanisms with the feed shaft, means for automatically determining the extent of the movements of the spindle by said mechanisms, and a device 15 driven by the feed shaft and carrying said means.
